UNITED STATES PATENT OFFICE.

MORTIMER F. FLYNN, OF WEST NEW BRIGHTON, NEW YORK, ASSIGNOR TO NEW NAP SYSTEM, INC., OF NEW YORK, N. Y., A CORPORATION OF NEW YORK.

NAPPING MACHINE.

Application filed December 10, 1925. Serial No. 74,472.

This invention relates to napping machines.

An object of the invention is to provide an improved form of napping element of a re-napping machine of the hand propelled type and an improved form of napping roll for bringing up a nap on cloth and other fabrics.

An especial feature of the present invention is the provision of a flexible base for the wire bristles, thus affording the utilization of so-called carding cloth, and suitable means for securing such carding cloth effectively economically and with a finished appearance to the rotary support of the napping machine.

A further advantage of a flexible base for the wire bristles resides in the availability of wire stock for the bristles of uniform extension in its direction of length, either for the whole of the body portion, or for the respective body portions provided with one or more "knees", the free ends of the respective bristles being provided with burrs or other hook-like terminations.

25 Preferably, the effective direction of extension of the body portions of the wire bristles is uniform and at an angle to the radius of the roller or other suitable support for the bristles.

30 Pursuant to the most preferred form of my invention, the wire bristles are disposed substantially uniformly in an indefinite length of cloth or other suitable flexible supporting material and of substantially uniform body dimension and configuration, from which an indefinite strip of the same is cut, such strip is then wound helically upon a hollow tube of suitable material and glued thereto, the hollow tube having a length equal to the desired multiple of the length of the individual roller of a single napping machine.

40 Such elongated hollow tube with the strip of napping members is then severed for the respective napping machines. Such severing may be attained by the use of a rotary grinder and on a lathe or the like. The resulting severed sections are then mounted upon rollers of wood or other suitable material and secured thereto by gluing or the like and each roller is mounted on a shaft of steel or the like. The flexible base may be mounted directly on the roller if desired.

45 The present invention attains simplified constructions of reduced costs of manufacture as will appear.

Further features and objects of the invention will be more fully understood from the following detail description and the accompanying drawings, in which

50 Fig. 1 is a vertical sectional view of a manual type of a napping machine embodying my invention;

Fig. 2 is a sectional elevation on line 2—2 of Fig. 1;

Fig. 3 is a detail perspective view showing 65 a portion of the abrasive bar and its supporting means indicated in Figs. 1 and 2;

Fig. 4 is a sectional elevation on line 4—4 of Fig. 2 on a greatly enlarged scale; and

Fig. 5, 6 and 7 are detail sectional elevations 70 showing modified forms of the body portions of the bristles or other napping members.

Referring to Figs. 1 to 4, inclusive, the napping machine embodying my invention as 75 applied to the hand propelled type as illustrated, comprises a frame 10 provided with a handle 11. The casing includes the upper and substantially horizontal casing portion 12 and the oppositely disposed depending, 80 substantially vertical casing portions 13, 14.

The napping element comprises the individual wire bristles 15 of the desired body outline, the inner ends 16 of which are lodged within the one or more thicknesses of cloth 85 17 or the like. The wire bristles are of uniform stock of gage wire of suitable material and are conveniently protruded through the flexible base material 17 and bent to have a U-shape, pursuant to approved methods. 90

In Fig. 4, each bristle 15 has its body portion extending substantially rectilinearly from its inner end 16 to its free end, at which latter end a burr 19 is formed as described more fully hereinafter. Preferably, the body 95 portion of each bristle 15 of the form illustrated in Fig. 4, has its inner end portion 16 extending at the desired angle denoted at 20 to the opposite flat faces of the flexible base material 17, so that when the flexible base 100 material 17 is applied about a circular support as described more fully hereinafter, each burr 19 is disposed, and in this case each body portion 15 extends, at the desired angle 20 to the radius of the circular portion 105 and consequent radius of the flexible base material 17.

In a similar manner, other forms of the body portions of the wire bristles may be employed. In Fig. 5, the wire bristles have 110

their inner body portions 21 bent to a straight line to form an angle to the portions 22 of the bristles exterior of the flexible base material 17, thus forming a "knee" 23 substantially at 5 the outer face of the flexible base material 17. The direction of extension of the rectilinear body portion 22 of the bristles is at the desired angle similar to the angle 20 of Fig. 4, or other appropriate angle. The burrs at the 10 free ends of the bristles are indicated at 19. In Fig. 6, the wire bristles are formed to have the knees 24 a substantial distance beyond the outer face of the flexible base material 17, the material of the inner portion 25 of each 15 bristle extending through the flexible base material 17 and the outer portion 26 of each bristle extending at an angle to the inward part. In a similar manner, other configurations of the respective inner and outer portions of each bristle may be selected to attain the objects of the invention.

After the flexible base material 17 and the bristles have been mounted on the circular support, as described more fully hereinafter, 20 the burrs are formed by a suitable grinding device and preferably of the nature set forth in my copending application Serial No. 34,811, entitled Machine for napping fabrics, filed by me on the 4th day of June, 1925, and 25 now Patent No. 1,583,587 whereby the burrs project from the bristles in a direction opposite to that of the rotation of the circular support in its movement of napping. That is to 30 say, as viewed in Fig. 1, the direction of propulsion of the napping machine manually is indicated by the arrow 27 for the effective stroke of napping by the wire bristles, and accordingly, the direction of rotation of the 35 cylindrical support is that of the arrow 28, as is indicated in Fig. 4. Accordingly, in 40 the effective stroke of napping, the burrs 19 are projected within the woven structure, see 29, Fig. 4, to a predetermined depth and upon the continued rotation of the cylindrical roller and therewith the flexible base 45 support 17 as indicated by the arrow 28, the burrs 19 are withdrawn from the warp and weft of the woven structure, as indicated at 50 the location 30, the fibres of the warp and weft threads being pulled by the burrs and resulting in the bringing up of the nap indicated at 31. By the feature of the extension 55 of the body portions, see 15, Fig. 4, at a substantially uniform angle to the radius of the circular support, the burrs are moved in the direction of withdrawal of the bristles from 60 the woven fabric 29 at an acute angle to the lower portions of the respective bristles, thereby releasing the caught fibres of the warp and weft threads gently without tearing and with substantially uniform pressure and direction of movement, and resulting in the production of a substantially uniform nap 31.

65 The uniformity of the produced nap is fur-

ther facilitated by maintaining substantial uniformity of sharpness of the respective burrs 19 and maintaining substantially uniformity of projection of the burrs 19 from the body portions of the bristles, which results are readily effected by the provision of an abrasive 32, as in the form of a flat strip of suitable abrasive material such as a bar 32 of high tempered steel or the like and preferably carried by the casing 10 in adjustable relation therewith. In the form as illustrated in Figs. 1, 2 and 3, the abrasive bar 32 extends substantially the full length of the napping member, and may be in the form of a metal bar of the desired outline as indicated 70 and providing for the upturned, oppositely disposed extensions 34, 35 which project through suitable slotted openings in the upper portion 12 of the frame 10 of the napping machine; these slotted openings serve to 75 guide the extensions 34, 35 in the radial movement of the abrasive 32 relatively to the radius of the cylindrical napping member when pressed by the adjustable set screw 36 passing through the threaded opening 37 in 80 the upper frame portion 12.

It will be observed that upon the rotation of the napping member, each wire bristle is brought in contact with the abrasive once for every complete rotation and that successive 95 complete rows of bristles lengthwise of the roll are brought in contact with the abrasive.

The abrasive serves also to restore to position any wire bristle which may have been displaced in its position. Preferably, as 100 above indicated, the wire bristles are disposed substantially at uniform distances from one another, to attain substantially uniform distribution of the burrs or other hook-like terminations at the free ends of the bristles. 105

In the use of my manually propelled type of napping machine, the length of the napping roll or napping member is usually less than the width of the garment, fabric, cloth or other article to be re-napped, and in order to cover the full surface of the article to be re-napped, the napping machine is moved laterally, that is to say, in a direction transverse to the direction of propulsion.

In lieu of the use of burrs of the nature 115 of the aforesaid burrs 19, the wire bristles may be provided with hook ends 38, as indicated in Fig. 7, the body portions of the wire bristles conforming to any of the various forms referred to hereinabove. In Fig. 120 7, the body portions of the wire bristles correspond to those indicated in Fig. 4. It will be observed that the flexible base material 17 is illustrated in Fig. 7, as flat, as is also illustrated in Figs. 5 and 6; that is to 125 say, the position of the flexible base material as illustrated in Figs. 5, 6 and 7 is that assumed by it prior to being applied to a cylindrical support.

I prefer to form the cylindrical base of 130

my napping member by applying an indefinite length of strip of the flexible base material 17 firstly about a hollow tubing 41 of suitable material, such as fibre, papier mâché or like material, which is capable of being severed by a circular grinder having a thin cutting edge. Assuming the length of the resultant napping element to be two inches, applicable for napping machines for restoring nap, that is to say, re-napping nap-bare garments and the like, the length of the hollow mounting tubing is selected for a multiple of such napping element length, say, six, eight, or ten inches, of course allowing for the thickness of the body portion of the grinder in the resulting waste. Such strip of what I identify herein as "carding cloth" is wound helically about the mounting tubing and secured thereto by glue or the like. The helical winding is indicated by the dotted lines 40, shown in Fig. 2; in this instance, the width of the strip is substantially $\frac{1}{6}$ of the length of the napping element, and it will be understood that the width of the strip relative to the length of the napping member may be selected as preferred.

The use of a thin rotary grinder overcomes entirely the disadvantages attending the use 30 of a saw or the like or by cutting by a knife, namely, in obviating the tearing of the wire or the cloth or of the tubular mounting material or in distorting of any wire, and in avoiding ragged edges and ends. The severing 35 of the napping cloth and the tubular mounting material is had by rotating the same in a lathe or the like to travel in the same direction as the grinder at the location of severing contact.

Upon severing the combined "carding cloth" and the length of the tubular mounting means indicated at 41 in Fig. 2, the same is then mounted on a roller 42 of wood or like material and glued or otherwise secured thereto, and through the central opening 43 of the roller 42 is passed the pin 44. The pin 44 may be secured to the roller 42 and thereby to the flexible base material by any suitable means or procedure, or the pin 44 may be loosely positioned within the roller 42 as is indicated in Fig. 2, in which latter instance, one end 45 of the pin 44 may be threaded to mesh with the threading of the opening 46 in the side flange 13 of the machine frame 10 and a nut 47 tightened to the projecting portion of threaded end 45. The threaded end 45 may be reduced in diameter relative to the body portion of the pin 44 to provide for the shoulder 48 abutting the inner face of the portion of the side flange 13 about the opening 46. The opposite end 49 of the pin 44 is journalled in a suitable opening in the opposite side flange 14; the end 49 of the pin 65 44 may be provided with a key slot 50 to

facilitate tightening and untightening the pin 44.

The lateral severed faces of the roller 42, the mounting tubing 41 and of the flexible base material 17 are concealed by the face 70 disks 51, 52 which may be secured in position by the nails 53.

In the form of my invention illustrated in Figs. 1 and 2, the abrasive 32 is mounted and applied in a manner which has been selected from the viewpoint of economy of cost of material and labor. With such form of abrasive and mounting means therefore, and for other purposes, the "drag" effective upon the individual napping members 75 in their operation of napping is adjusted in magnitude by the provision of a regulatable brake. For the purpose, I have illustrated the roller 42 as having the circular extension 54 of reduced diameter, the circular face 80 of which may be covered with metal, over which is passed the strip 55 of thin steel or like resilient metal serving as a brake band, the opposite ends 56 of the strip 55 being provided with suitable openings for receiving the eye 57 of one end of the coiled retractile spring 58, the opposite, hooked end 59 of which is received within the opening of the adjustable screw 60 passing through the threaded opening 61 of the upper casing portion 12. By turning the adjustable screw 60 outwardly of the frame portion 12, the spring 58 is increased in tension, thereby increasing the frictional force between the 90 brake band 55 and the extension 54 of the roller 42 and thereby increasing the "drag" of the wire bristles relative to the material to be napped. The lessening of the "drag" is attained by turning the regulating screw 60 inwardly of the frame portion 12. 100

The adjusting screw 60 serves also to compensate the position of the abrasive 32 for the extent of wear of wire bristles.

In carrying out my invention in the various forms of the hand propelled type hereinabove described, as indicated hereinafter, the stroke of effective napping of a thread-bare spot on a garment or the like is in the direction of rotation 28 of the napping member, and in the manner of assembly of the handle 11 on the machine frame 10, in the direction of travel 110 27 of the handle. The movement of the handle 11 in its opposite direction and the consequent opposite rotation of the napping member to that of the arrow 28, is not effective in producing a nap or in re-napping, and may be readily carried out while the napping members are in contact with the garment or the like without injury to the weaving or the old or reformed nap, which latter action is made 115 possible by the feature of the relation of extension of the burrs relative to the body portion of the bristles. 120

As appears from my invention, as above described, the use of cloth or other suitable ma- 130

terial serving as a flexible base for the wire bristles, the flexibility of the material of the wire bristles is enhanced. Such arrangement affords the employment of wire stock of highly tempered steel having the property of taking and retaining a sharp burr.

My invention enables the use of the so-called carding cloth in the form of a napping cylinder, and accordingly attains economies 10 in the cost of the napping material.

Whereas, I have described my invention by reference to specific forms thereof, it will be understood that many changes and modifications may be made without departing from 15 the spirit of the invention.

I claim:

1. A method of forming a bristle covering for a napping roller, comprising the steps of 20 taking tubular cylindrical fibrous material serving as the mounting material having a length equal to a multiple of the length of the napping roll, helically winding and securing on the periphery of said cylindrical mounting material an indefinite length of flexible base material to which the inner ends of 25 the napping members are secured, and severing the cylindrical mounting material into individual roll covering sections by applying a circular grinder at locations corresponding 30 to said roll length.

2. The method of forming a napping roller of a determined length, which comprises taking tubular cylindrical mounting material having a length equal to a multiple of the 35 length of the napping roll, helically winding and securing on the periphery of said cylindrical mounting material an indefinite length of flexible base material to which the inner ends of the napping members are secured, and applying a circular grinder at locations 40 corresponding to said determined length whereby the individual rolls of determined length are produced.

3. The method of forming a napping roller 45 of a determined length, which comprises taking cylindrical fibrous tubing mounting material having a length equal to a multiple of said determined length, helically winding and securing on the periphery of said cylindrical mounting material an indefinite length of flexible base material to which the inner ends 50 of the napping members are secured and applying a circular grinder at locations corresponding to said determined length, whereby the individual tubular sections of determined length are produced, and mounting the tubular sections upon suitable cylindrical supports.

4. The combination of a cylindrical roller, 60 a flexible base on said roller, bristles mounted on said flexible base and at a predetermined angle relative to the radius of the roller, means for rotatably supporting said roller, means serving jointly for applying a drag 65 to said wire bristles and for restoring the an-

gular relation of any bristle deranged relative to said roller, and means for supporting said drag applying and bristle angle restoring means at a location to effect contact with the ends of said bristles between their respective successive stages of napping. 70

5. The combination of a cylindrical roller, a flexible base on said roller, bristles mounted on said flexible base and at a predetermined angle relative to the radius of the roller, 75 means for rotatably supporting said roller, adjustable means serving jointly for applying a drag to the ends of said wire bristles and for restoring the predetermined angular relation of any bristle deranged relative to said 80 roller and means for supporting said drag applying and bristle angle restoring means at a location to effect substantially uniform contact with the ends of said bristles between their respective successive stages of napping. 85

6. The combination of a cylindrical roller, flexible material wound spirally on said roller, bristles mounted in said spiral flexible material at a predetermined angle relative to the radius of the roller, means for rotatably 90 supporting said roller, means serving jointly for applying a drag to said wire bristles and for re-sharpening the ends of same and means for supporting said drag applying and bristle re-sharpening means at a location to effect 95 contact with the ends of said bristles between their respective successive stages of napping.

7. The combination of a cylindrical roller, flexible material wound spirally on said roller, bristles mounted in said spiral flexible 100 material at a predetermined angle relative to the radius of the roller, adjustable means serving jointly for applying a drag to said wire bristles and for re-sharpening the ends of same and means for supporting said drag applying and bristle 105 re-sharpening means at a location to effect contact with the ends of said bristles between their respective successive stages of napping.

8. The combination of a housing having 110 means for manual propulsion, a plurality of napping members of suitable material, a flexible base mounting means for increasing the resiliency of said napping members, rotatable means for mounting said flexible base in said housing, means for re-sharpening the said napping members and means for supporting said re-sharpening means in the said housing so as to be in contact with the ends of all of the napping members during each revolution 115 of the rotatably mounted member.

9. The combination of a housing having means for manual propulsion, a plurality of napping members of suitable material, with their free ends buried, a flexible base mounting means for increasing the resiliency of said napping members, rotatable means for mounting said flexible base in said housing, means for re-sharpening the burrs of the 125 said napping members, and means for sup- 130

porting said re-sharpening means in the said housing so as to be in contact with the burrs of all of the napping members during each revolution of the rotatably mounted member.

- 5 10. The combination of a housing having means for manual propulsion, a plurality of napping members of suitable material, with their free ends burred, a flexible base mounting means for increasing the resiliency of said 10 napping members, rotatable means for mounting said flexible base in said housing, said napping members extending at such an angle to the radius of the rotatable member as to enter the material to be napped in a

spear-like manner as the rotatable member 15 passes over it, means for re-sharpening the burred ends of said napping members, means for supporting said re-sharpening means in the said housing so as to be in contact with the burrs of all of the napping members during 20 each revolution of the rotatably mounted member and means for adjusting said re-sharpening means to compensate for the wear of the napping members.

In testimony whereof I have signed this 25 specification this 30th day of Nov., 1925.

MORTIMER F. FLYNN.
